METHOD FOR THE PRODUCTION OF
WATER GAS

Edward S. Roberts, New York, N. Y., John B. Rinckhoff, Fanwood, N. J., and Frederick C. Cunningham, Jackson Heights, N. Y., assignors to Chemical Construction Corporation, New York, N. Y., a corporation of Delaware

Application June 4, 1946, Serial No. 674,198

4 Claims. (Cl. 48—206)

1

This invention relates to a method for the production of water gas from coal and more particularly to a method of producing continuously from coal a water gas substantially free of nitrogen.

It has been proposed to gasify coal by introducing into a producer containing coal a hot mixture of air and steam and by the decomposition of the steam and a controlled burning of the coal to generate a producer gas containing carbon monoxide and hydrogen. Such gas is diluted with relatively high percentages of carbon dioxide and nitrogen, however. There have been further proposals to make water gas by reacting coal with steam in a water gas producer by introducing into a producer containing coal a heated mixture of steam and a recycled portion of the water gas. The recycled water gas functions as an inert heat carrier so that enough heat for the reaction can be carried to the producer by the mixture of steam and water gas.

It has been suggested that a reverberatory type heater such as a Cowper heater be used to heat the gases entering the producer. The operation of such apparatus is cyclic in nature and imposes limitation on the proposed processes for gasifying coal. The heated gases entering the producer are subject to temperature and pressure fluctuations. The pressure fluctuation interferes with the operation of the suspended solid bed type of producer and the temperature fluctuations prevent the continuous application of the maximum attainable temperature to these gases. Both these factors result in a product gas of relatively non-uniform composition and low volume efficiency in the apparatus.

It is a principal object of our invention to provide a method for the production of a high heating value water gas substantially free of nitrogen and consisting predominantly of hydrogen and carbon monoxide by a method which substantially completely gasifies coal by introducing into a producer containing coal a mixture of steam and water gas heated to water gas reaction temperature in a heat exchanger having movable discrete heat exchange solids. Other objects are to provide a method for the production of water gas of uniform composition and to provide water gas suitable for the Fischer-Tropsch process. Still another object is to provide apparatus having a high volume efficiency by supplying a mixture of steam and water gas to a water gas producer at the maximum attainable temperature.

With the above and other objects in view, 55

2

the invention therefore consists in the various process steps and combinations thereof and in the various arrangements and combinations of apparatus elements hereinafter to be specifically described with particular reference to preferred embodiments thereof and illustrated in the accompanying drawing.

In its broader aspects our invention comprises a method of producing from coal a substantially 10 nitrogen-free water gas by reacting coal with steam at water gas reaction temperatures in a gas producer to form a hot water gas consisting predominantly of hydrogen and carbon monoxide, recovering part of the hot water gas as product 15 gas, admixing the remainder with steam and contacting this mixture with movable discrete heat exchange solids in a gas heating zone to heat the mixture to a water gas reaction temperature, passing the hot mixture to the water 20 gas producer, the heat exchange solids having been heated to a temperature above the desired water gas reaction temperature by introducing them into the path of hot products of combustion in a solids heating zone.

25 Apparatus for carrying out the method comprises in combination a water gas producer and heat transfer means including movable discrete heat exchange solids with means in a solids heating zone to heat the solids to a temperature 30 above the desired water gas reaction temperature with hot products of combustion, means to remove the heated solids to a gas heating zone and means to heat a mixture of steam and water gas to the desired water gas reaction temperature 35 in the gas heating zone by contact with the heated solids, means to return the heat exchange solids from the gas heating zone to the solids heating zone and means to pass the heated mixture of steam and water gas to the producer, 40 means to generate water gas in the producer by reacting the hot mixture with coal, means to recover as product gas a part of the water gas produced therein, means to recycle the remainder of the gas with steam to form the mixture of 45 steam and water gas which is used to gasify coal in the water gas producer.

Essentially our invention is a method of producing from coal a substantially nitrogen-free water gas which comprises reacting coal with 50 steam at a water gas reaction temperature in a gas producer to form a hot water gas consisting predominantly of hydrogen and carbon monoxide. The hot water gas is partially cooled by passing it in contact with a mass of relatively cool, movable discrete heat exchange solids in a

solids preheating zone and the preheated solids are then removed to a solids heating zone where they are heated to temperatures above the desired water gas reaction temperature by contacting them with hot products of combustion. The partially cooled water gas is further cooled by passing in heat exchange relationship with preheated water to generate steam after which it is divided into two streams. One stream is mixed with a portion of the generated steam and recycled through a gas heating zone to the gas producer where it reacts with coal to produce more water gas. The recycled gas is heated to the desired water gas reaction temperature by introducing the hot heat exchange solids from the solids heating zone into the path of the mixture in the gas heating zone. The second stream of the cooled water gas is scrubbed and further divided into two streams, one of which is withdrawn as product gas from this process. The second stream of the scrubbed gas is mixed with preheated air and the combustible mixture is burned in the solids heating zone and thereby the heat exchange solids therein are heated to a temperature above the desired water gas reaction temperature. The hot products of combustion from the solids heating zone pass in heat exchange relationship with air to preheat the air that is mixed with the water gas which is burned in the solids heating zone. After preheating air, the products of combustion are divided into two streams, one which is vented to open air after contacting coal which is thereby dried and passed to the gas producer. The other stream is also vented to open air passing in heat relationship with water which is thereby reheated. The preheated water is passed in heat exchange relationship with the partially cooled water gas from the solids preheating zone as described above.

Apparatus in which our method may be carried out is shown in the accompanying drawing, the single figure of which is a flow sheet in which various pieces of equipment are illustrated diagrammatically. It should be understood, however, that the drawing is given primarily for illustration purposes and that our invention in its broader aspects is not limited thereto.

Referring to the drawing which represents the preferred embodiment of the invention, 1 is a water gas producer of the suspended solids type. Any type of producer may be used such as a fluid bed or slagging producer with various up or down draft modifications. The Winkler type producer may be used and 1 is a diagrammatic drawing partly in section of a modified Winkler type water gas producer.

The preferred heat transfer means is pebble heater 2 shown partly in section. It consists of a suitably insulated vertical tower with a restricted diameter at throats 7 and 8 which cooperate to form a pebble preheating zone 3, a pebble heating zone 4, and a gas heating zone 5. Pebbles 6 which fill the tower almost to the top of section 3 are free to flow from one section to another depending upon the rate at which they are withdrawn from the bottom of section 5 and returned to the top of section 3 by a conveyor. Any suitable conveyor system may be used. Thus, for example, the pebbles from the bottom of section 5 pass through pipe 57 at a rate controlled by the star valve 58 into conveyor 59 which may be of the bucket or screw conveyor type which are available commercially, and then through pipe 60 into the top of section 3. A motor (not shown) or any other suitable

means may be used to rotate the star valve 57. The rate of circulation of the pebbles depends upon the heat requirements of the several heating zones.

5 In passing through pebble heater 2, the pebbles 6 are heated in pebble preheating section 3 by the hot water gas from producer 1 and pass through throat 7 to pebble heating zone 4 where they are heated by contact with hot products of combustion, obtained by burning combustible material therein, to a temperature above the desired water gas reaction temperature. The hot pebbles then pass through throat 8 to gas heating section 5 where they are brought into contact with the mixture of steam and water gas and heat this mixture to the desired temperature.

10 It is obvious that the gases in the different heating sections of pebble heater 2 should not be allowed to mix and this is prevented by the restricted cross-section at the throats and by operating the apparatus in such a way that the pressure on one side of the throats 7 and 8 is equal to the pressure on the other side. Instead 15 of the throats 7 and 8 which are the preferred connecting means between the section, a system of gas-tight conveyors may be used.

15 By means of pebble heater 2, a mixture of steam and water gas is supplied to producer 1 at a uniform pressure and temperature. In 20 order to obtain the greatest efficiency in the apparatus and in the reaction, it is desirable that the mixture of steam and water gas be supplied to the producer continuously and uniformly at 25 the maximum attainable temperature. One of the principal advantages of our invention is that by combining a pebble heater with a gas producer, the mixture can be supplied continuously to the producer at a temperature limited only 30 by the softening point of the pebbles. Another important advantage is that because of the uniformity of the temperature of the mixture of steam and water gas, the composition of the 35 product gas is uniform.

40 As stated above, 1 is a water gas producer in which coal is reacted with steam to produce hot water gas. The hot gas leaves producer 1 through pipe 9 and passes through dust collector 10 where substantially all of the dust and ash 45 carried by the water gas is allowed to separate and is removed from the dust collector through outlet 11. The substantially dust-free gas passes from the dust collector 10 through pipe 12 and into the highest or pebble preheating section 3 50 of the three-section pebble heater 2. In section 3 the gasified coal gives up a part of its sensible heat to the pebbles therein and is passed through pipe 14 to steam boiler 15 where most of the 55 remaining sensible heat in the gas is used to generate steam. The gas leaves boiler 15 through pipe 16 and a portion of the gas is drawn off through pipe 17 and into scrubber 18. The remainder of the gas continues through pipe 18 60 and passes through the blower 19 and into pipe 65 20 where it is admixed with controlled quantities of steam that enters pipe 20 through pipe 40 and is passed into the lowest or gas heating section 5 of the pebble heater 2. The mixture 70 is heated by the hot pebbles in section 5 to a desired water gas reaction temperature and is passed through pipe 21 to the water gas producer.

The portion of the water gas entering scrubbing tower 18 through pipe 17 is washed with water or weak alkali solution which enters the 75 scrubber through pipe 22 and spray nozzle 23.

The scrubbing liquid plus any dust it may have removed from the gas leaves the scrubber through outlet pipe 56. A portion of the scrubbed gas is withdrawn from scrubber 18 through pipe 24 and recovered as product gas. The remaining portion may be withdrawn through pipe 25 and is passed through blower 26 and through pipe 27 into pipe 28 where it admixes with pre-heated air and passes into the middle or pebble heating section 4 of the pebble heater 2.

Atmospheric air is drawn through blower 29 and is passed through pipe 30 into air preheater 31 where the air is preheated. Air preheater 31 is a tubular type preheater with the air to be heated passing around and in contact with tubes 32 through which pass the hot products of combustion. The preheated air is withdrawn from the preheater through pipe 28 and admixes with fuel entering pipe 28 from pipe 27. The mixture continues through pipe 28 and enters section 4 as described above. The mixture is burned in section 4 of the pebble heater 2 and part of the heat of combustion is absorbed by the pebbles in this section. The products of combustion are withdrawn from section 4 through pipe 33 and pass through the tubes 32 in air preheater 31 where a portion of the sensible heat in the products of combustion is used to preheat the air.

The gaseous products of combustion are withdrawn from the air preheater 31 through pipe 34 from which a portion of the gases are withdrawn through pipe 35 and pass through the water preheater 36 and are then vented to the open air through the vent pipe 37. Water enters the tubular preheater 36 through pipe 38 and is pre-heated and passed through pipe 39 to the steam boiler 15 and is converted into steam. Steam as necessary is withdrawn from boiler 15 through pipe 40 and enters pipe 20 where it admixes with water gas. Any excess steam is withdrawn from boiler 15 by pipe 54 and is available for any suitable use.

The remaining portion of the products of combustion that are not withdrawn through pipe 35 continue through pipe 34 to coal drier 41 where the hot gases are used to dry coal and are then vented to the open air through vent pipe 42. Coal that is to be dried enters coal drier 41 through inlet 43. After being dried, the coal passes through pipe 44 to screw conveyor 45 from which it is fed into water gas producer 1. If it is desired to reduce the temperature of the gases entering the drier 41, part or all of the cool products of combustion from vent pipe 37 may be returned to pipe 34 by a valved by-pass.

The producer 1 is a diagrammatic drawing partly in section of a modification of the Winkler water gas producer. As illustrated, the producer is a circular chamber having suitable refractory lining 46 and a grate 47 which is wiped with a revolving scraper 48. The rotating motion of the scraper 48 is imparted by the housed revolving shaft 49 on which is mounted a gear 50 which is driven by a motor (not shown). The mixture of steam and water gas that has been heated in section 5 of pebble heater 2 to a water gas reaction temperature enters the producer 1 through pipe 21 and passes up through spaces 55 in grate 47 and into contact with a bed of coal 51 where the coal is gasified by steam to form gases containing predominantly carbon monoxide and hydrogen. The coal bed 51 is of the solid suspension type and part of the ash that forms as the coal is gasified settles on grate 47 and is removed from the grate by scraper 48 and drops into

hopper 52 from which it is removed by screw conveyor 53. The remainder of the dust is carried by the water gas and substantially all of it is removed in dust collector 10.

5 The process as carried out in the apparatus shown in this drawing may be operated to produce excess heat. The excess heat is introduced into the system by burning an excess of combustible material in section 4 of pebble heater 2 and appears as excess steam in boiler 15. The excess can be withdrawn through pipe 54 and put to any desirable use.

15 There are a number of ways of operating the apparatus other than the preferred way described and shown by the drawings. Thus for example, the recycled portion of the water gas may be led directly into pipe 20 from pipe 14 and the pump 19 may be replaced by a high pressure, high temperature steam injector which would supply steam and pressure for the steam and water gas mixture at the same time. In this method of operating, the steam boiler would be placed in line 17 and the unrecycled gases would generate steam before being scrubbed. 20 Another example is that section 3 of pebble heater 2 may be eliminated and in this case the gas from dust collector 10 would pass directly into pipe 14 and process may then be carried out as described in the first part of this paragraph. 25 These examples are given to illustrate the flexibility of the apparatus and method of the invention and are not intended to limit the scope of the invention.

30 The following data are given as an example of the operation of the method when carried out in the apparatus shown in the drawing. Enough dried coal at 150° C. from drier 41 to contain 58.4 atomic equivalents of carbon and hydrogen of which 62.7 atomic percent is carbon and 37.3 atomic percent is hydrogen is introduced into the water gas producer 1. With each 58.4 atomic equivalents of the carbon and hydrogen in the dried coal 295 mols of a mixture of recycled water gas and steam at 1430° C. are reacted in producer 1 to generate 343 mols of water gas which leave the producer 1 at 900° C. and contain 32% CO, 4% CO₂, 57.2% H₂ and 10.4% water by volume. The hot water gas passes to section 3 of pebble heater 2 where it heats the pebbles and leaves the section at 410° C. The gas then passes to steam generator 15 where it generates steam and leaves at 210° C. 243 mols of the 343 mols of the water gas are recycled through blower 19 after which it mixes with 52 mols of steam at 125° C. and the mixture at 190° C. enters section 5 of pebble heater 2 where it is heated to 1430° C. and is passed at that temperature to producer 1.

55 The 100 mols of water gas at 210° C. remaining from the 343 mols leaving the steam generator 60 15 pass to scrubber 18. On a dry basis 52 mols of the scrubbed gas are withdrawn at 25° C. as product gas having a composition of 35.7% CO, 5.4% CO₂, and 58.4% by volume hydrogen and a heating value of about 300 B. t. u. per cubic foot.

65 The remaining portion of the 100 mols amounting to 38 mols on the dry basis passes to combustion section 4 of the pebble heater 2 and is mixed with 270 mols of air that has been pre-heated in the tubular preheater 31 to a temperature of 825° C. The mixture of water gas and air burns in section 4 to produce 292 mols of gaseous products of combustion which leave this section at 925° C. The products of combustion or flue gases pass through the air preheater 31, entering the heater at 925° C. and

leaving at 200° C. 142 mols of flue gas leaving tubular heater 31 pass through water preheater 36 leaving the preheater at 135° C. at which temperature it is vented to the open air. 52 mols of water at 20° C. are heated to 100° C. by the 142 mols of flue gas passing through the preheater 36. The 52 mols of water pass to steam generator 15 where they are converted to 52 mols of steam at 125° C. and 36 pounds per square inch pressure. This quantity of steam is mixed with 242.5 mols of recycled water gas as described above.

The remaining 150 mols of the 292 mols of flue gas which is at 200° C. and which leaves the air preheater 31 pass to coal drier 41 where coal containing 5% water is dried. The 100 mols of flue gas increase to 150 mols of flue gas and water at 160° C. which is vented to the air.

Lignite, coke and hydrocarbon-bearing shales in addition to any type of coal may be used in the water gas producer 1 but it is preferred to use the fine coal that is usually discarded at the mine or sold at very low prices. It is possible to use the coal in any size but fine or pulverized coal is preferred and also it is preferred to operate the apparatus in the vicinity of the coal mining fields so that the fine coal produced in handling coal and the discarded coal produced in the mining operation may be used.

It will be noted that our invention provides a method for the production of substantially nitrogen-free water gas containing predominantly hydrogen and carbon monoxide by heating in a pebble heater a mixture of steam and recycled water gas to water gas reaction temperatures and reacting the heated mixture with coal in a water gas producer. It will be noted also that the method makes possible the continuous production of water gas of a uniform controllable composition and that a water gas can be produced which has a consistent heat value of about 300 B. t. u. per cubic foot and that a gas can be produced which is suitable for the Fischer-Tropsch Synthesis or methane production. The method has further utility in that it can be used to produce a gas containing a hydrogen content high enough to be used as a source of hydrogen for hydrogenation processes or for the synthetic production of fatty acids.

What we claim is:

1. A method of producing from coal a substantially nitrogen-free water gas which comprises reacting coal with steam at water gas reaction temperatures in a gas producer to form a hot water gas consisting predominantly of hydrogen and carbon monoxide, passing said hot water gas in contact with a mass of relatively cool, movable discrete heat exchange solids in a solids preheating zone, removing the resulting preheated solids to a solids heating zone and heating them to a temperature above the desired water gas reaction temperatures by contact with hot products of combustion therein, separating the cooled water gas into a plurality of streams, adding steam to one of said streams and recycling it through a gas heating zone and back to the gas producer for reaction with coal, heating the recycled gas to water gas reaction temperatures by introducing the hot heat exchange solids into the path of said recycled gas in said gas heating zone removing the solids from the gas heating zone and recycling them to said solids preheating zone, and withdrawing a second stream of said cooled water gas as product gas from the process.

2. A method of producing from coal a substan-

tially nitrogen-free water gas which comprises reacting coal with steam at water gas reaction temperatures in a gas producer to form a hot water gas consisting predominantly of hydrogen and carbon monoxide, passing said hot water gas in contact with a mass of relatively cool, movable discrete heat exchange solids in a solids preheating zone, removing the resulting preheated solids to a solids heating zone and heating them to a temperature above the desired water gas reaction temperature by contact with hot products of combustion therein, further cooling the partially cooled water gas by passing it in heat exchange relationship with water to form steam from said water, separating the cooled water gas into a plurality of streams, adding a portion of said generated steam to one of said streams and recycling it through a gas heating zone and back to the gas producer for reaction with coal, heating the recycled gas to water gas reaction temperatures by introducing the hot heat exchange solids from said solids heating zone into the path thereof in said gas heating zone removing the solids from the gas heating zone and recycling them to said solids preheating zone and withdrawing a second stream of said cooled water gas as product gas from the process.

3. A method of producing from coal a substantially nitrogen-free water gas which comprises reacting coal with steam at water gas reaction temperatures in a gas producer to form a hot water gas consisting predominantly of hydrogen and carbon monoxide, passing said hot water gas in contact with a mass of relatively cool, movable discrete heat exchange solids in a solids preheating zone, removing the resulting preheated solids to a solids heating zone and heating them to a temperature above the desired water gas reaction temperatures by contact with hot products of combustion obtained by burning combustible material with preheated air in said solids heating zone, cooling said hot products of combustion from said solids heating zone by passing them in heat relationship with air, passing the resulting preheated air into said solids heating zone, separating the relatively cooled products of combustion into a plurality of streams, discarding one stream, passing another of said streams in drying contact with coal, then discarding the stream, passing said dried coal to said gas producer, further cooling the partially cooled water gas from said solids preheating zone by passing it in heat exchange relationship with water to form steam, separating the cooled water gas into a plurality of streams, adding a portion of said generated steam to one of said streams and recycling it through a gas heating zone and back to the gas producer for reaction with coal, heating the recycled gas to water gas reaction temperatures by introducing the hot heat exchange solids into the path of said recycled gas in said gas heating zone removing the solids from the gas heating zone and recycling them to said solids preheating zone and withdrawing a second stream of said cooled water gas as product gas from the process.

4. A method of producing from coal a substantially nitrogen-free water gas which comprises reacting coal with steam at water gas reaction temperatures in a gas producer to form a hot water gas consisting predominantly of hydrogen and carbon monoxide, passing said hot water gas in contact with a mass of relatively cool, movable discrete heat exchange solids in a solids preheating zone, removing the resulting preheated solids

to a solids heating zone and heating them to a temperature above the desired water gas reaction temperature by contact with hot products of combustion obtained by burning a portion of said water gas with preheated air in said solids heating zone, cooling said hot products of combustion from said solids heating zone by passing them in heat relationship with air, passing the resulting preheated air into said combustion zone, separating the relatively cooled products of combustion into a plurality of streams, discarding one of said streams, passing another in drying contact with coal, then discarding this stream, passing said dried coal to said gas producer, further cooling the partially cooled water gas from said solids preheating zone by passing it in heat exchange relationship with water to form steam, separating the cooled water gas into two streams, adding a portion of said generated steam to one of said streams and recycling it through a gas heating zone and back to the gas producer for reaction with coal, heating the recycled gas to water gas reaction temperatures by introduc-

5
10
15
ing the hot exchange solids in the path of said recycled gas in said gas heating zone removing the solids from the gas heating zone and recycling them to said solids preheating zone, washing and scrubbing the second stream of said water gas, separating it into two streams, mixing one of said streams with said preheated air and passing the mixture to said solids heating zone and withdrawing the remaining stream as product gas from the process.
